(57) **CLAIM**

The ornamental design for a travel mug contoured to mouth, as shown and described.

DESCRIPTION

FIG. 1 is a left side view of the travel mug contoured to mouth of the present invention showing my new design;

FIG. 2 is a right side view thereof;

FIG. 3 is a rear view thereof;

FIG. 4 is a front view thereof;

FIG. 5 is a top view thereof;

FIG. 6 is a bottom view thereof; and,

FIG. 7 is a perspective view thereof.

The broken lines in FIGS. 1–4, FIG. 6 and FIG. 7 that depict the body of the travel mug represent environment and are not claimed subject matter.

The broken lines in FIGS. 5 and 7 that depict the push-button at the center of the top and that depict the air hole at the top represent environment and are not claimed subject matter.
